UNITED STATES PATENT OFFICE.

OSKAR FINKHAUS, OF WURZBURG, GERMANY, ASSIGNOR TO BOHN & HERBER, MASCHINENFABRIK UND EISENGIESEREI, OF WURZBURG, BAVARIA, GERMANY, A KOMMANDITGESELLSCHAFT OF GERMAN LAW.

HIGH-SPEED CYLINDER PRINTING PRESS.

Application filed August 2, 1924. Serial No. 729,811.

To all whom it may concern:

Be it known that I, OSKAR FINKHAUS, a citizen of Deutsches Reich, and residing at 34 Petrini Street, Wurzburg, Bavaria, Germany, have invented certain new and useful Improvements in High-Speed Cylinder Printing Presses, of which the following is a specification.

This invention relates to high speed cylinder printing presses, namely to those with the printing cylinder rotating always in the same direction and with the printed sheets discharged at the front of the machine.

The object of the invention is to render it possible for the machine minder whilst standing straight in front of the machine in an easy attitude, to watch the printed sheet which is directly in front of him, and the screws for regulating the delivery of ink which are also directly in front of him, and to adjust the said screws.

The invention has for its further object to make it possible for the machine minder to carry out, without any danger and effort, with the greatest speed and reliability and without leaving his place, the regulation throughout the whole width of the printing and to eliminate at once during the running of the machine any trouble in the delivery of ink that becomes noticeable. Wrong positions of the screws for regulating the delivery of ink are obviated as the longitudinal strips of the sheet and the screws regulating the delivery of ink to these longitudinal strips are situated in the same direction before the eyes of the machine minder. In this way, mistakes in printing are avoided, and the quality of the product improved.

These advantages are preferably obtained in an inking apparatus which does not contain any reciprocating distributing table. Thus the consumption of power of the machine is reduced owing to the elimination of the great weight of the reciprocating distributing table or board.

In order to obtain this and other improvements hereinafter described the ink duct is mounted under the delivery board, and both are arranged close to the front edge of the machine, and the rest of the inking apparatus is made so shallow that it can be accommodated under the taking off device which moves the sheet horizontally, a bed

without a distributing table being preferably employed.

The accompanying drawing shows two constructions of those parts of a well known high speed cylinder printing press which are effected by the invention.

Figure 1 is a diagrammatic longitudinal section through the front part of the machine of one construction and

Figure 2 a similar view of a second construction.

In the drawing *a* is the delivery board and *b* the printing cylinder of a high speed cylinder press, always rotating in one and the same direction; *d* a taking-off device of any desired construction which conveys the printed sheet in a practically horizontal direction from the printing cylinder to the delivery board and *e* is the reciprocating carriage of the machine. This carriage is not provided with any distributing table. The delivery board *a* is arranged on the front of the machine. Under the taking-off device *d* is arranged the inking apparatus. The beginning of the inking device is constituted by the ink duct *f* of the well known construction which is mounted under the delivery board *a*. Both are arranged close to the front of the machine. The duct or roller (or vibrator) *h* supplies ink from the ink duct to a preliminary distributing roller *r*. A second duct or roller *v* in the construction shown in Figure 1 moves between the preliminary distributing roller *r* and a fixed distributing roller *z*. The roller *v* rolls over the fixed ink distributing table *t* backwards and forwards; it is operated by a fork *g* driven by the reciprocating carriage *e*.

In the construction shown in Figure 2 the duct or roller or vibrator *v* travels between the preliminary distributing roller *r* and a fixed distributing roller *z'* which transmits the ink by means of a cylinder *i* to a second distributing roller *z''* and by means of another cylinder *k* to the fixed distributing roller *z*. From the distributing roller *z* the ink passes, in both constructions, to the inking rollers *x* from whence it is taken by the form.

When the machine minder takes up his usual working position in front of the machine he can see whilst standing normally the printed sheets all the way from the

printing cylinder over the taking-off device *d* and after their laying on the delivery board *a*, and can make sure whether the right quantity of ink is everywhere or whether 5 single longitudinal strips of the print get too much or too little ink. Without changing his place and his position, he can eliminate then any faults in a convenient attitude by means of the regulating screws *f'* 10 on the ink duct *f* and can always compare the position of the faulty strips of the print with the position of those regulating screws *f'* which he has to change.

The inking apparatus in both constructions is built so shallow that it can be accommodated under the taking-off device and delivery table. In the construction shown in Figure 1 it is a table inking device with a fixed distributing table over which rolls to 20 and fro the duct or roller *v*. In the construction shown in Figure 2, the inking device is constituted exclusively by rollers. In the former case, it has all the advantages of the table inking devices without the drawback 25 that the reciprocation of the heavy distributing table unfavorably affects the running of the machine and consumes a good deal of power. The weight of the roller *v* with the fork *g* is very small relatively to 30 that of the distributing table.

The invention has among others also the advantage that the inking device at the front of the machine and the laying-on table at the rear of the machine do not project beyond 35 the end positions of the carriage driving frame. The machine therefore is as short as it is possible to make it with due regard to the length of printing.

Having now particularly described and 40 ascertained the nature of my said invention and in what manner the same is to be performed I declare that what I claim is:—

1. In a one-color high speed cylinder printing press, the combination of a stationary printing cylinder always rotating in one direction, with a taking-off device directed 45 towards the front of the machine, a delivery table near the front edge of the machine, an inking device in which all the movable and ink conducting surfaces are cylindrical and 50 under the taking-off device, an ink duct, said

duct mounted under the delivery table and close to the front edge of the machine and a reciprocating carriage coacting with said printing cylinder. 55

2. In a one-color high speed cylinder press, the combination of a stationary printing cylinder always rotating in the same direction, with a taking-off device directed towards the front of the machine, and moving the sheet substantially in a horizontal direction, a delivery table close to the front edge of the machine, an inking device in which all the movable and ink conducting surfaces are cylindrical and under the taking-off device, an ink duct, said duct mounted under the delivery table and close to the front edge of the machine, and a reciprocating carriage coacting with said inking device and printing cylinder. 60 65

3. In a one-color high speed cylinder printing press, the combination of a printing cylinder always rotating in the same direction, with a taking-off device directed towards the front of the machine, a delivery table close to the front edge of the machine, an inking device in which all the movable and ink conducting surfaces are cylindrical and provided with a fixed distributing table under the taking-off device, an ink duct 70 mounted under the delivery table and close to the front edge of the machine, and a carriage. 75 80

4. In a one-color high speed cylinder printing press, the combination of a printing cylinder always rotating in the same direction, with a taking-off device directed towards the front of the machine, a delivery table close to the front edge of the machine, an inking device in which all the movable and ink conducting surfaces are cylindrical and provided with a fixed distributing table under the taking-off device, an ink duct 85 mounted under the delivery table and close to the front edge of the machine, a carriage, 90 and a duct or roller travelling to and fro on said fixed distributing table, and a fork 95 engaging said roller and actuated by said carriage.

In testimony whereof I have affixed my 100 signature.

OSKAR FINKHAUS.
